[57] **CLAIM**

The ornamental design for a wall plate-concentric margin, as shown and described.

DESCRIPTION

FIG. 1 is a perspective photographic view of a wall plate for a switch illustrating my new design.

FIG. 2 is a front elevational photographic view of the wall plate of FIG. 1.

FIG. 3 is a rear elevational view of the wall plate of FIG. 1.

FIG. 4 is a side elevational view of the wall plate as in FIG. 1.

FIG. 5 is an end plan view of the wall plate of FIG. 1. FIG. 6 is a front elevational view of a wall plate for a wall receptacle illustrating my new design.

FIG. 7 is a front elevational view of a wall plate for two side-by-side switches illustrating my new design.
